JOHN COOK, OF BROOKLYN, NEW YORK.

Design No. 3,384, dated February 23, 1869.

DESIGN FOR A SPOON OR FORK-HANDLE.

The Schedule referred to in these Letters Patent and making part of the same.

To all whom it may concern:

Be it known that I, JOHN COOK, of Brooklyn, in the county of Kings, in the State of New York, have originated and designed a new and original Form and Pattern for Handles for Table-Sets, such as for handles for spoons, knives, forks, ladles, &c., of which the following is a full, clear, and exact description, reference being had to the accompanying drawing, making part of this specification.

The nature of my design for articles which compose table-sets, such as spoons, forks, knives, ladles, &c., is more in regard to its general outline, especially the member *a*, or end of the handle.

The handle, in its outline, is so formed and indented as to consist of the sections *a*, which forms the extreme end, *b*, which forms a middle, or connecting-section, and *c*, the lower section, which is made to ta-

per or conform to the article to which it is to form the handle.

The beading and ornamentation made thereon harmonize with the form of outline, but are not the essential feature of the design, as that may be varied upon the same outline.

Having thus described my new design for handle for table-sets,

What I claim as my invention, and desire to secure by Letters Patent, is—

The design or pattern for handle for table-sets, herein set forth and shown.

JOHN COOK.
